(57) **CLAIM**

The ornamental design for a pillow travel tote, as shown and described.

DESCRIPTION

FIG. 1 is a right front view of my new pillow travel tote.

FIG. 2 is a view of the interior of the pillow travel tote expanded to show extended flaps, attached pillowcase, interior pockets and a means of closure.

FIG. 3 is a view of the exterior of the pillow travel tote expanded to show extended flaps, exterior pockets and a means of closure; and,

FIG. 4 is a view of the pillow travel tote in the in-use position showing the main body reversed, pillowcase exposed, and straps and exterior pockets hidden to the inside.

My pillow travel tote is characterized by the ability to contain a soft, removable, fiberfill, pillow in its pillowcase and the ability to reverse the main body keeping items stored in the pockets secure while using the pillow.
